UNITED STATES PATENT OFFICE.

EZRA E. CLARK, OF NEWTONVILLE, MASSACHUSETTS, ASSIGNOR TO FRANK J. FEE,
OF NEW ROCHELLE, NEW YORK.

VALVE-LOCKING MECHANISM FOR DRY-PIPE VALVES.

Application filed July 24, 1922. Serial No. 576,948.

This invention relates to improvements in dry pipe valves of the type which are employed in automatic sprinkler systems and which include a water valve and an air valve of larger area than the water valve, so constructed and positioned that the pressure of air confined in the sprinkler system will hold the water valve closed against the pressure of water in the supply pipe.

10 Dry pipe valves of this general character are provided with means for guiding the valve structure, upon release of the air pressure in the sprinkler system, to a position outside of the waterway so that the water will flow freely from the supply pipe through the outlet of the casing and the connecting pipes to the sprinkler system.

In certain types of dry pipe valves, such, for example, as that illustrated in my prior 20 Patent No. 1,450,428 granted April 3, 1923, means are provided for supporting the water valve and the air valve in such a manner that the movement of the valves from closed to open position causes a relative movement, usually an angular movement, of one valve relatively to the other.

The principal object of the present invention is to provide means for locking the valves against such angular movement when 30 the valve structure is swung to open position so that they cannot be returned to closed position by a reverse flow of the column of water leading from the dry pipe valve to the sprinkler heads in case the water supply entering the dry pipe valve casing is diverted by the opening of a second dry pipe valve, or for any other reason.

A further object of the invention is to provide a novel locking mechanism for accomplishing this purpose acting by the influence of gravity as the valves are swung to open position.

A further feature of the invention consists in providing conveniently operable 45 means for releasing the locking means when it is desired to restore the valves to closed position.

A further object of the invention is to provide an improved means for restraining the 50 locked valve structure when in open position from a pivotal closing movement.

Other objects and features of the invention will more fully appear from the fol-

lowing description and the accompanying drawing and will be particularly pointed out in the claims.

The drawing illustrates in vertical section a preferred embodiment of the invention applied to a dry pipe valve structure of the type illustrated in my prior Patent No. 1,450,428 aforesaid.

The dry pipe valve illustrated in the accompanying drawing comprises a body portion or casing 1 which is provided at its upper end with an outlet 2 adapted to be connected to an automatic sprinkler system normally containing air under pressure. The lower end of the casing is provided with an inlet conduit 3 adapted to be connected to the usual riser pipe of the water supply which is always under pressure. The inlet and outlet openings 3 and 2 preferably are in alignment so that a substantially straight waterway is provided through the casing for the water which is forced therethrough upon unseating of the air and water valves by the release of a sprinkler head and consequent reduction of air pressure in the sprinkler system.

The casing is provided with a lateral extension 4, providing a chamber to receive the valves when in open position, having a large aperture therethrough through which the valves may be introduced and removed, said aperture being provided with a removable cover 5.

The end of the inlet conduit 3 is provided with a water valve seat 6 which preferably lies in a plane normal to the axis of the inlet conduit. The casing is also provided with an air valve seat 7, of considerably larger diameter than the water valve seat, which surrounds the water valve seat and preferably is located in a plane oblique to the plane of the water valve seat.

The water valve 6 is connected by a stud 8 to the end portion of a swinging supporting and guiding arm 9, the lower end of which is provided with a shaft or laterally projecting studs 10 which are pivotally mounted in a slotted bearing 11 in a bracket 12 projecting from the side of the inlet conduit 3. Preferably the connection between the stud 8 upon the water valve and the arm 9 is slightly loose to enable a sufficient rocking of the valve to

insure proper seating thereof upon the valve seat.

The air valve 13 preferably is of concaved form and surrounds and partially encloses the water valve and its supporting and guiding arm. The air valve is pivotally mounted upon a shaft 14 which extends through and is journaled in a suitable bearing 15 in the arm 9. The lower portion of the air valve is provided with a bifurcated extension or pair of arms 16 between which a roller 17 is mounted upon a shaft 18 supported or journaled in said arms. Preferably the end portions of the arms 16 present a curved surface of the same radius and conforming to the curvature of the periphery of the roller 17.

The lower portion of the chamber 4 extends downwardly into the form of a pocket 19 providing a guideway for the extension of the air valve. This guideway desirably is provided with a substantially vertical wall having a central track 20 for the roller 17 and recessed portions 21 at either side of the track to prevent engagement of the rounded end portions of the arms 16 with the wall of the guideway. The bottom of the guideway desirably is provided with a V-shaped seat 22 to receive the air valve extensions 16 when the valve structure is swung to open position.

In the operation of the device the swinging movement of the valves from closed to open position causes the water valve to be moved about the pivot 10 of the arm 9 to the position illustrated in dotted lines. During this movement of the water valve from closed to open position the air valve is moved relatively to the water valve by reason of its pivotal connection with the arm 9 and the engagement of the roller 17 upon the air valve extension with the track 20 of the guideway so that when the valves are swung to open position the face of the air valve will be substantially in parallelism with the face of the water valve as illustrated in dotted lines.

The principal object of the present invention, as above stated, is to provide means for locking the air valve and water valve against relative movement when swung to open position thereby preventing the closing of the valves by a reverse flow of the column of water leading to the sprinkler system in case the water supply entering the easing is diverted by the opening of a second dry pipe valve or for any other reason.

Any suitable means may be provided for locking the air valve and water valve against such relative movement within the scope of the present invention. The preferred mechanism which is illustrated herein comprises interengaging locking members which are so constructed and positioned as to be engaged by the force of gravity dur-

ing the movement and particularly at the conclusion of the movement of the valves to open position.

In the particular construction illustrated the locking mechanism comprises a pawl 23 combined with a counterweight which is pivotally supported by or upon a shaft 24 carried by lugs or ears 25 which project upwardly from the pivotally mounted arm 9 which supports and guides the water valve. The pawl is provided at one end, the left as shown, with a central projection or tooth 26 presenting a notch or shoulder which is positioned to engage a shoulder 27 projecting inwardly from the inner face of the concave air valve 13 when the valve is swung to the position illustrated in dotted lines in the drawing.

The body of the pawl 23 desirably is cored to provide a chamber 28 to receive a weight of lead or other heavy material which may be poured into the chamber through suitable apertures 29 in the pawl. The pawl thus weighted normally rests upon the arm 9 as illustrated in full lines in the drawing when the valves are in closed position. When, however, the valves are swung toward open position the weighted pawl swings about its pivot 24 so that the notch of the tooth 26 engages the shoulder 27 which projects inwardly from the inner face of the concave air valve 13, thus locking the water and air valves together as illustrated in dotted lines in the drawing.

In order that the pawl may be conveniently released from engagement with the shoulder 27 when it is desired to reset the valves in closed position the pawl 23 is provided with a downwardly extending arm 30 having a laterally extending handle 31 which may be conveniently grasped by the operator and actuated to swing the pawl about its pivot from the dotted line position to the full line position illustrated in the drawing. In thus manipulating the pawl the operator passes his hand through the opening in the easing and reaches around the edge of the air valve to manipulate the handle 31.

It will be remembered that during the movement of the valves from closed to open position a relative angular movement between the air valve and water valve is produced and the shoulder 27 is so positioned upon the air valve that when the valve structure is swung to open position the tooth 26 will engage the shoulder 27 and effectively lock the air and water valves against relative movement thereby preventing the valves from again swinging to closed position in case a reverse flow of the column of water causes a pressure upon the valves which otherwise would tend to swing them to closed position.

In order to prevent possibility of the locked valve structure from swinging about the pivot 19 of the arm 9 means are pro-

vided to engage the roller 17 on the extension 16 and prevent such swinging movement of the valve structure as a whole.

In the preferred construction illustrated 5 this guide comprises a curved projection or horn 32 which is secured to or formed integral with the cover 5 and extends into the guideway adjacent to the path of the extension 16 and roller 17 of the air valve and 10 preferably slightly overlies the wall of the V-shaped seat for said extension so that in case the valve structure has a tendency to swing about the pivot 10, by reason of reverse flow of the water through the casing, 15 the roller 17 on the extension 16 will engage the face of the projection or horn and be arrested against further movement.

It will be noted that the valve structure is wholly mounted upon the pivotal shaft 10 20 which is journalled in the slotted bearing 11 so that the valve structure as an entirety can be readily inserted and removed through the aperture 4 when the cover has been taken off. When, however, the valve structure 25 has been assembled in the casing the upper overhanging wall 33 of the journal 11 acts to prevent displacement of the valve structure.

The back of the air valve also desirably is 30 provided with a preferably centrally disposed rib 34 and the cover 5 is provided with a complementary web or rib 35, the face of which lies closely adjacent to the path of the rib 34 on the air valve when the air valve 35 is swung to open position. These ribs are so positioned as to co-operate in guiding the valves to open position and also prevent displacement of the valves when locked in open position if the dry pipe valve is turned 40 over as is likely to occur in transportation.

It will be understood that the embodiment 45 of the invention disclosed herein is of an illustrative character and is not restrictive and that various modifications in form, construction and arrangement of parts may be made within the spirit and scope of the following claims.

Having thus described my invention, what I claim as new, and desire to secure by Letters Patent, is:

1. A dry pipe valve comprising a casing having a waterway therethrough and provided with a water valve seat and an air valve seat, a water valve and an air valve 55 angularly movable relatively to each other, means for conjointly supporting and guiding said valves from closed position to an open position out of the waterway and acting to vary the relative positions of said valves during their movement to open position and means movable relatively to said valve supporting means for automatically locking said valves together during the movement to open position whereby said 60 valves will be prevented from closing.

2. A dry pipe valve comprising a casing having a waterway therethrough and provided with a water valve seat and an air valve seat, a water valve and an air valve angularly movable relatively to each other, 70 means for conjointly supporting and guiding said valves from closed position to an open position out of the waterway and acting to vary the relative positions of said valves during their movement to open position, locking mechanism movable relatively to said valve supporting means by the action of gravity into interengagement during the movement of said valves from closed to open position and 75 acting when engaged to lock said valves together and to prevent relative angular movement of said valves in the reverse direction and thereby to prevent closing of 80 said valves.

3. A dry pipe valve comprising a casing having a waterway therethrough and provided with a water valve seat and an air valve seat, a water valve, means including an arm pivotally connected to said water valve for supporting said valve and guiding the same from closed to open position, an air valve pivotally mounted on said arm, means for varying the angular relation of 90 said air valve to said water valve during the 95 movements of said valves to open position and co-operating locking members carried respectively by said arm and air valve and movable relatively thereto into interengaging position as the valves open thereby to 100 prevent said valves from closing.

4. A dry pipe valve comprising a casing having a waterway therethrough and provided with a water valve seat and air valve seat, a water valve, means including an arm 105 pivotally connected to said water valve for supporting said valve and guiding the same from closed to open position, an air valve pivotally mounted on said arm, means for varying the angular relation of said air valve 110 to said water valve during the movements of said valves to open position, a gravity pawl pivotally mounted on said arm and a shoulder on said air valve positioned to be engaged by said pawl during the movement of the 115 valves to open position and acting to prevent said valves from closing.

5. A dry pipe valve comprising a casing having a waterway therethrough and provided with a water valve seat and an air 120 valve seat surrounding said water valve seat and located in a plane oblique to the plane of said water valve seat, a water valve, means including a swinging arm pivotally connected to said water valve acting 125 to support said valve and guide the same from closed to open position, a concave air valve surrounding said water valve pivotally mounted on said arm, guiding means engaging said air valve acting to cause rela- 130

- tive angular movement between said air valve and said water valve during the movement of said valves to open position, a gravity pawl mounted on said arm located under said air valve and a shoulder on said air valve positioned to be engaged by said pawl during the movement of said valves toward open position and thereby to prevent said valves from closing.
6. A dry pipe valve comprising a casing having a waterway therethrough and provided with a water valve seat and an air valve seat surrounding said water valve seat and located in a plane oblique to the plane 15 of said water valve seat, a water valve, means including a swinging arm pivotally connected to said water valve acting to support said valve and guide the same from closed to open position, a concave air valve 20 surrounding said water valve pivotally mounted on said arm, guiding means engaging said air valve acting to cause relative angular movement between said air valve and said water valve during the movement 25 of said valves to open position, a gravity pawl mounted on said arm located under said air valve and a shoulder on said air valve positioned to be engaged by said pawl during the movement of said valves toward 30 open position and thereby to prevent said valves from closing and an arm on said pawl adapted to be grasped by the operator to release said pawl from engagement with said shoulder.
7. A dry pipe valve comprising a casing having a waterway therethrough, a water valve seat and an air valve seat surrounding said water valve seat and located in a plane oblique to the plane of said water valve seat, 35 and a chamber to receive the valves when in open position having a downwardly extending guideway and provided with an opening having a removable cover to permit introduction and removal of the valves, a water 40 valve, a detachable pivotal arm connected to said water valve acting to support said water valve and to guide the same into said chamber, an air valve pivotally mounted upon and surrounding said arm, an extension on 45 said air valve positioned to enter said guideway during the opening of said valves and acting to cause relative angular movement between said valves during their movement to open position, means operable during the movement of said valves to open position to lock said valves against relative angular movement and means located upon said removable cover positioned to engage said air valve extension acting to prevent closing movement of the locked valve structure.
8. A dry pipe valve comprising a casing having a waterway therethrough, a water valve seat and an air valve seat surrounding said water valve seat and located in a plane oblique to the plane of said water valve 50 seat, and a chamber to receive the valves when in open position having a downwardly extending guideway and provided with an opening having a removable cover to permit introduction and removal of the valves, a water valve, a detachable pivotal arm connected to said water valve acting to support said water valve and to guide the same into said chamber, an air valve pivotally mounted upon and surrounding said arm, an extension on 55 said air valve positioned to enter said guideway during the opening of said valves and acting to cause relative angular movement between said valves during their movement to open position, means operable during the movement of said valves to open position to lock said valves against relative angular movement, a seat having converging walls at the bottom of said guideway to receive and contact with said air valve extension when the valves are in open position and prevent displacement of the valves from open position, an opening in the wall of said chamber and a cover for said opening having guiding means projecting into said guideway positioned to engage said air valve extension and prevent pivotal closing movement of said locked valves, but removable with said cover to permit introduction and removal of the valves from the casing.
- In testimony whereof, I have signed my name to this specification.
- EZRA E. CLARK.
